CLAIM

I claim the ornamental design for an ejector finger for a cap feeder, as shown and described.

DESCRIPTION

FIG. 1 is a front view of a first embodiment of the ejector finger for a cap feeder in accordance with my new design;

FIG. 2 is a left side view thereof;

FIG. 3 is a bottom view thereof;

FIG. 4 is a top plan view thereof;

FIG. 5 is a back view thereof;

FIG. 6 is a right perspective view thereof; and

FIG. 7 is a back right perspective thereof.

FIG. 8 is a front view of a second embodiment of the ejector finger for a cap feeder in accordance with my new design;

FIG. 9 is a left side view thereof;

FIG. 10 is a bottom view thereof;

FIG. 11 is a top plan view thereof;

FIG. 12 is a back view thereof;

FIG. 13 is a right perspective view thereof; and,

FIG. 14 is a back right perspective thereof.

The broken lines show portions of an ejector finger for a cap feeder that form no part of the claimed design.
